(57) **CLAIM**

The ornamental design for a lid assembly with a reclosable drink opening, substantially as shown and described.

DESCRIPTION

FIG. 1 is a top perspective view of the lid assembly of this invention with the sliding member thereof in its closed position;

FIG. 2 is a top view of the lid assembly of FIG. 1;

FIG. 3 is a bottom perspective view of the lid assembly of FIG. 1;

FIG. 4 is a view in elevation of the lid assembly of FIG. 1 along line 4—4 of FIG. 2;

FIG. 5 is another view in elevation of the lid assembly of FIG. 1 along line 5—5 of FIG. 2;

FIG. 6 is another view in elevation of the lid assembly of FIG. 1 along line 6—6 of FIG. 2;

FIG. 7 is a top perspective view of the lid assembly with the sliding member thereof in its open position;

FIG. 8 is a top perspective view of the cover element of the lid assembly of this invention; and,

FIG. 9 is a top view of the cover element of FIG. 8.

Broken lines in FIGS. 1 through 9 form no part of the claimed design.

1 Claim, 6 Drawing Sheets
